Primary Examiner — Cynthia M Chin(74) *Attorney, Agent, or Firm* — Montgomery Patent & Design; Robert C. Montgomery(57) **CLAIM**

The ornamental design for a stationary motorcycle toy, as shown and described.

DESCRIPTION

FIG. 1 is an isometric view of a stationary motorcycle toy, showing my new design;

FIG. 2 is a front view thereof;

FIG. 3 is a rear view thereof;

FIG. 4 is a left hand view thereof, wherein the right hand view is a mirror image thereof;

FIG. 5 is a top view thereof; and,

FIG. 6 is a bottom view thereof.

The broken lines represent portions of the article that form no part of the claim.
